UNITED STATES PATENT OFFICE.

HENRY A. MINER, OF MALDEN, MASSACHUSETTS, ASSIGNOR TO MINER'S FRUIT NECTAR CO., OF SAME PLACE.

DESIGN FOR A DISPENSING-JAR STAND.

SPECIFICATION forming part of Design No 28,117, dated January 4, 1898.

Application filed December 22, 1896. Serial No. 616,665. Term of patent 7 years.

To all whom it may concern:

Be it known that I, HENRY A. MINER, a citizen of the United States, residing at Malden, in the county of Middlesex and State of Massachusetts, have invented and produced a new and original Design for a Stand for Dispensing Jars or Receptacles, of which the following is a specification, reference being had to the accompanying drawing, where the figure 10 is a view in elevation of a stand for a dispensing jar or receptacle containing my design.

The leading features of my design comprise the base for the jar or receptacle in the form of a holder consisting of a circular foot-section A, surmounted by a tile a, and three rods

a' a² a³, extending upward from said foot-section, arranged in a triangular relation to each other and connected with each other at a⁵ by a connection having an annular shape.

Having thus fully described my invention, 20 I claim and desire to secure by Letters Patent of the United States—

The design for a dispensing-jar stand having the circular base, the triangularly-placed supporting-rods and the annular connection, 25 substantially as described and shown.

HENRY A. MINER.

In presence of—

F. F. RAYMOND, 2d,
J. M. DOLAN.
